UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

STATIC-POTENTIAL-CONTROLLING APPARATUS.

Application filed June 14, 1919. Serial No. 304,308.

To all whom it may concern:

Be it known that I, ROBERT M. GILSON, a citizen of the United States, residing at Pittsburgh, in the county of Allegheny and State of Pennsylvania, have invented certain new and useful Improvements in Static-Potential-Controlling Apparatus, of which the following is a specification.

My invention relates to static potential controlling apparatus, and particularly to apparatus for controlling the potential applied to current-consuming devices which are known to be limited as to life. Such devices may, for example, be electric lamps, tungar rectifiers, or other devices, comprising heated filaments, although I do not wish to be limited to any particular character of current consuming device.

One object of my invention is the provision of means having no contacts or other moving parts, for placing a reserve current-consuming device in service when a device which has previously been in service ceases to function.

I will describe several forms of apparatus embodying my invention, and will then point out the novel features thereof in claims.

In the accompanying drawings, Fig. 1 is a diagrammatic view showing one form of apparatus embodying my invention. Fig. 2 is a view partly diagrammatic, showing another form of apparatus embodying my invention. Fig. 3 is a diagrammatic view showing apparatus which is the electrical equivalent of the apparatus shown in Fig. 2. Fig. 4 is a view showing apparatus which is the equivalent of that shown in Fig. 3. Fig. 5 is a view showing a modification of the apparatus shown in Fig. 2 and also embodying my invention. Fig. 6 is a view similar to Fig. 5 but showing two reserve lamps instead of one.

Similar reference characters refer to similar parts in each of the several views.

Referring first to Fig. 1, the reference character T' designates a transformer, the secondary of which is connected with a current-consuming device L', which, as here shown, is an incandescent lamp. This lamp L' will be hereinafter referred to as the "main" lamp. The primary of the transformer T' is supplied with alternating current by suitable means, such as the second-

ary of a transformer T² whose primary is connected with a source of alternating current which is not shown in the drawing. Suitable means are provided for limiting the amount of current supplied to transformer T', this means as here shown being a reactance R interposed between the two transformers. A reserve current-consuming device L², also in the form of an incandescent lamp, is connected across the terminals of the primary of transformer T'. 55 60 65

The parts of the apparatus shown in Fig. 1 may be so proportioned that while lamp L' is burning at normal voltage the voltage applied to the reserve lamp L² is considerably below normal, but that when lamp L' burns out, the voltage applied to lamp L² will be increased to the normal value so that this lamp will then burn at normal brilliancy. As an example, I have found that this result may be attained by proportioning the parts as follows:

I will assume that each lamp L' and L² is of the tungsten filament type and that these lamps are of about two candle power, taking .2 ampere at 10 volts, lamps of this type 80 and size being the ones which are customarily used for semaphore lighting in railway signaling. The resistance of each lamp when hot, is, of course 50 ohms. If the transformer T' is made with a 1:2 ratio, and if the voltage of the secondary is 10 volts, it follows that when lamp L' is burning the current flowing in the primary will be .4 ampere. The potential across the primary of transformer T' is then, of course, 5 volts, 85 so that the voltage applied to lamp L² is then half of the normal value. While lamp L² is supplied with half of its normal voltage, its resistance will be about 75% of its resistance when hot; that is, about 37.5 ohms. 90 The current flowing in lamp L² is, therefore 95

5 which equals .13 ampere. I will, furthermore, assume that the exciting current for transformer T' is 20% of the load 100 current, that is, .08 ampere at .4 power factor, and that this exciting current increases in proportion to the applied voltage. It will be found by computation, or by the construction of a vector diagram, that the total 105 current flowing in reactance R is then about .56 ampere. I will assume that the power factor of the reactance R is .1 and that the

value of this reactance is about 23 ohms. If the potential at the secondary of transformer T^2 is 15 volts, the result will be a potential of 10 volts across lamp L' , while this lamp 5 is burning.

When lamp L' burns out, there will be a potential of 15 volts applied to a circuit composed of the reactance R in series with an impedance composed of lamp L^2 and the 10 primary of transformer T' in multiple. Assuming that lamp L^2 now burns at 10 volts, its resistance will be 50 ohms at unity power factor. The impedance of the primary of transformer T' is

$$15 \quad \frac{5}{.08}$$

which equals 62.5 ohms at .4 power factor. To combine these two impedances in multiple it is necessary to determine the admittance of each branch. The admittance of 20 the lamp L^2 is

$$\frac{1}{50} = .02.$$

25 The admittance of the primary of transformer T' is

$$\frac{1}{62.5} = .016.$$

30 By computation or by vector diagram it will be found that the combined admittance of these two impedances is .03, at an angle of 29 degrees. The combined impedance of 35 lamp L^2 and the primary of transformer T' is therefore

$$\frac{1}{.03} = 33.3 \text{ ohms.}$$

40 this impedance also being at an angle of 29 degrees. To this must be added the impedance of the coil R (23 ohms at .1 power factor). The total impedance in the circuit will then be found to be about 50 ohms. 45 The current flowing in the circuit is therefore

$$\frac{15}{50} = .3 \text{ ampere.}$$

50 It follows that the potential across lamp L^2 and across the primary of transformer T' is $.3 \times 33.3 = 10$ volts, which is the desired voltage at this lamp after lamp L' burns out.

Referring now to Fig. 2, the apparatus 55 in the form here shown comprises a reactive transformer having a core 3, a primary winding 4, two secondary windings 5 and 6, and a magnetic shunt 7 around that portion of the core on which the primary 60 4 is wound. Lamp L' is connected with secondary 5 and lamp L^2 is connected with secondary 6, the number of turns in the secondary 5 being twice the number of turns in the secondary 6. The primary winding 65 4 is connected with a suitable source of alter-

nating current, which is not shown in the drawing.

It is a well known fact that a reactive transformer is electrically equivalent to a constant potential transformer with a reactance interposed between the secondary and the load. In the electrical equivalent, the voltage across the load is the same as the voltage on the secondary of the reactive transformer when loaded. The voltage 70 across the reactance in the equivalent apparatus is the same as the voltage which would be produced in the secondary of the reactive transformer by the flux which traversed the leakage path. A reactive 75 transformer with two secondaries, such as that shown in Fig. 2, may also be represented by electrically equivalent apparatus, but since the flux in the leakage path is diverted from both secondary windings, it is 80 necessary in the equivalent apparatus to use the same reactance for both loads, the number of turns of the reactance connected in series with each load being in proportion to the number of turns in the two secondaries. The electrical equivalent of the 85 apparatus of Fig. 2 is shown in Fig. 3.

In considering the apparatus shown in Fig. 2, I will assume as before that while lamp L' is burning the potential applied thereto is 10 volts, so that at such time the potential applied to the reserve lamp L^2 is 5 volts. Referring now to Fig. 3, I have found that the potential produced in the secondary $W-V$ should be about 21.8 volts, and that the value of the reactance R' should be about 70 ohms. The drop across this reactance will then be 18.5 volts, due to the combined effect of the main lamp current of 0.2 ampere flowing through the entire coil 95 and the reserve lamp current of 0.13 ampere flowing through one-half of the coil. When lamp L' burns out, lamp L^2 is connected through one-half of reactance R' and the 100 ohmic value of this portion of the reactance 105 is one-fourth of the value of the entire reactance or 17.5 ohms. The potential applied to lamp L^2 will then be 10 volts approximately, and this lamp will receive a current of .2 ampere.

Inasmuch as the apparatus shown in Fig. 2 is the electrical equivalent of that shown in Fig. 3, it is obvious that the magnetic shunt 7 in Fig. 2 can be so proportioned 110 as to cause the desired operation of the lamps L' and L^2 .

Referring again to Fig. 3, it will be observed that the points K and W are at the same potential because they are connected together. Inasmuch as the number of turns in secondary 6 is half the number of turns in secondary 5, it is obvious that the point E is at the same potential as the middle point Y in secondary 5. If, therefore, the secondary 5 is made of wire sufficiently 115 120 125

heavy to carry the currents for both lamps, it is evident that lamp L^2 may be connected between the points Y and P, and that the same results will then be obtained. This arrangement is shown in Fig. 4. The same values of voltage and current apply to Fig. 4 as to Fig. 3.

Inasmuch as the structure shown in Fig. 4 is the equivalent of that shown in Fig. 5 10 wherein a magnetic shunt 7 is substituted for reactance R' , it is obvious that the parts of the apparatus shown in Fig. 5 can be so proportioned that the lamps L' and L^2 will operate in the desired manner.

Fig. 6 is similar to Fig. 5, except that it 15 includes two reserve lamps L^2 and L^3 . Lamp L' is normally supplied with the proper operating voltage, whereas the voltages applied to lamps L^2 and L^3 is normally 20 considerably below the voltages on which they are designed to operate. When lamp L' burns out, the voltage applied to lamp L^2 will rise to the normal operating value, but the voltage applied to lamp L^3 will still 25 be below the normal operating value. When lamp L^2 subsequently burns out, the voltage applied to lamp L^3 will rise to the normal operating value.

Although in describing in detail the structure and operation of the various forms and apparatus, shown herein, I have referred to the current-consuming devices as incandescent lamps, it is understood that I do not limit myself to devices of this particular 30 type. Any current-consuming device or devices may be substituted for the lamps shown in the several views.

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. Static potential controlling apparatus comprising a reactive transformer, a main

current-consuming device connected with the secondary of said transformer, and a 50 reserve current-consuming device connected with a part only of said secondary winding, the parts being so proportioned that when the main device is operating the drop in potential due to the current taken thereby is 55 such that the potential applied to the reserve device is insufficient to operate it.

2. Static potential controlling apparatus comprising a transformer provided with means for limiting the amount of current flowing in the primary thereof, a main current-consuming device connected with the secondary of said transformer, and a reserve current-consuming device connected with a part only of said secondary. 60

3. Static potential controlling apparatus comprising a transformer, a main current-consuming device connected with the secondary of said transformer, and a reserve current-consuming device connected with a 70 part only of said secondary, the said elements being so proportioned that when the main device is operating the drop in potential across the transformer secondary due to the current taken by the main device is such 75 that the potential difference across the said part of the secondary is insufficient to operate the reserve device, but that when the main device is not operating the potential difference across the said part of the secondary automatically rises to a sufficient 80 value to operate the reserve device.

4. Static potential controlling apparatus comprising a transformer, a main current-consuming device connected with the secondary of said transformer, a reserve current-consuming device connected with a part only of said secondary, and a magnetic shunt on said transformer around the primary winding. 85

In testimony whereof I affix my signature in presence of two witnesses.

ROBERT M. GILSON.
